IMPACT SWITCH

Owen E. Grigsby, Park Ridge, Ill.

Application April 17, 1939, Serial No. 268,318

2 Claims.

(Cl. 200—52)

This invention relates to an impact switch and has particular application to automobiles, trucks, airplanes and the like. It is understood, of course, that the switch may be used in connection with other devices and for other purposes.

It is desirable to have automatic means for cutting off the ignition system on an internal combustion engine on vehicles and planes in the event of an accident. Thus, on trucks it is old to have a mercury switch in the ignition circuit which is adapted to open said circuit in the event of a sudden stopping or overturning of the vehicle. Such switches, however, are unsatisfactory for the reason that a series of impacts may reset the switch and undo the effect of the first impact. Furthermore, such switches are difficult to control and have been operated in many instances when the vehicle stops or starts suddenly or happens to go over some rough portion of the road. Under these conditions it is evident that operation of a switch of this character is not desired.

It is also desirable in many instances to have an impact switch operate some kind of an alarm in the event of an accident.

The switch described herein is particularly adapted for the above purposes since it may be adjusted to operate as the result of impacts of predetermined violence. Furthermore, the switch described herein will remain in its set position until changed by an impact and thereafter will not be returned to its reset position unless manually reset. The switch is simple and compact and may be set and reset in an easy and quick manner. Referring to the drawing:

Fig. 1 shows the switch in its case;

Fig. 2 is a section on line 2—2 of Fig. 1;

Fig. 3 is a view similar to Fig. 2 but showing the switch tripped after an impact;

Fig. 4 is a section similar to Fig. 2 but showing a modified form of switch; and

Fig. 5 is a section of the switch of Fig. 4 with the switch in tripped position.

The switch comprises a base 10 of any suitable rigid material which may be either metal or insulation. In the particular case shown base 10 is of metal. This base has provided a pair of apertures 11 and 12 in which bolts 13 and 14 are insulatingly mounted. Disposed on the inside of base 10 is an insulating block 15 suitably apertured, through which bolts 13 and 14 project. Rigidly carried by bolts 13 and 14 and insulating block 15 are a pair of fixed contact members 17 and 18. Beyond contact members 17 and 18 bolts 13 and 14 are provided with spacing nuts 19 and

20 and then pass through suitable apertures in an insulating block 21. The block 21 is suitably apertured at the center at 22 and may be provided with a metal bushing 23.

5 Disposed within aperture 22 of insulating block 21 is a plunger 25 preferably having the same cross-section as the aperture 22 and longitudinally movable within said aperture. Plunger 25 at the inner end thereof is provided with a flaring contact portion 26 of brass or other conducting material. As is clearly seen in Fig. 2, contact portion 26 is adapted to function as a movable contact and bridge the gap between stationary contacts 17 and 18.

10 15 Plunger 25 is provided with a recess 28 at the contact end thereof and within this recess a spring 29 is disposed. This spring bears against insulating strip 15 and, in order to maintain the spring properly centered, it is preferred to provide a small recess 30 in insulating strip 15. Preferably the outer end 31 of plunger 25 is cupped as shown in Fig. 2.

20 25 Supported by base 10 is a casing 32 of any suitable material such as metal. This casing 32 is provided with an aperture 33 opposite the plunger 25. A rubber grommet 35 is disposed in aperture 33 and through this a pin 36 is disposed. The outer end of pin 36 carries a knob 37 while the inner end carries a heavy inertia member 40 made of any suitable material such as iron, lead or brass if necessary. This member may have any desired shape and as shown is provided with a projecting head portion 41 adapted to fit into cup 31 of the plunger and a skirt portion 42 where the weight of the member is concentrated. A coil spring 45 is disposed around pin 36 and extends between weight 40 and a washer 47 around pin 36 bearing against grommet 35.

30 35 40 Bolts 13 and 14 are suitably insulated in the base 10 if the latter is metal by spacing as shown in the drawing and may be provided with binding terminals as shown.

45 40 Upon sufficient impact the heavy member 40 will be displaced from its normal position of Fig. 2 to the position shown in Fig. 3 thus permitting the movable contact member 26 to spring away and open the circuit. In order to reset the switch it is merely necessary to pull back plunger 36 by means of knob 37 and dispose member 40 in position as shown in Fig. 2.

50 45 The structures shown in Figs. 4 and 5 are generally similar to the structures shown in Figs. 2 and 3 with the exception that the stationary contact members 17' and 18' are disposed against

insulating block 21 so that normally the switch is open and will be closed upon impact as shown in Fig. 5.

The characteristics of the device may be controlled by the mass and shape of weight 40, tension of spring 45 and depth of cupped end 31. It is preferred to have skirt 42 so shaped that negligible cam action will occur against cupped member 25 tending to overcome spring 29. By having the angle between the sides and pin axis as small as possible, the tendency of the weight to straighten will merely exert a side thrust on cupped member 25. Any desired shape of weight may be used.

I claim:

1. An impact switch comprising a cup-shaped member and a detachable flat cover member cooperating to form a hollow enclosed chamber, a switch assembly mounted on one of said members, said switch assembly including stationary and movable contacts having open and closed positions and including a spring means for biasing said switch assembly to one of its two posi-

tions, said other member having an aperture opposite said spring means, a pin loosely mounted in said aperture, said pin having a knob on the outer end thereof and a weight on the inner end thereof, a coil spring around said pin between said other member and weight for spring biasing said pin and weight to an innermost position in said chamber, said weight and spring means having interfitting surfaces whereby said switch may be set by pulling said pin outwardly against its spring to set the interfitting surfaces against each other, said pin bias being sufficiently strong to overcome the switch assembly spring bias and set the switch to its other position, said impact switch having sufficient stability to remain in this set position until a shock to the structure occurs whereupon the weight is deflected from its set position to release the switch assembly.

2. The structure of claim 1 wherein said flat cover member carries the switch assembly and wherein the cup member is apertured and has a rubber grommet through which said pin projects.

OWEN E. GRIGSBY.
